UNITED STATES PATENT OFFICE.

LAYTON WATTON TOWNSEND, OF HAMILTON, ONTARIO, CANADA, ASSIGNOR TO
HENRY AITCHISON CHILMAN, OF HAMILTON, ONTARIO, CANADA.

COLLAPSIBLE HANGER.

1,346,922.

Specification of Letters Patent.

Patented July 20, 1920.

Application filed January 22, 1920. Serial No. 353,238.

To all whom it may concern:

Be it known that I, LAYTON WATTON TOWNSEND, a subject of the King of England, residing at Hamilton, in the Province of Ontario, Dominion of Canada, have invented certain new and useful Improvements in Collapsible Hangers; and I do hereby declare the following to be a full, clear, and exact description of my invention, such as will enable others skilled in the art to which it appertains to make and use the same.

My invention relates to hangers, and particularly to a hanger which may be taken apart, making it very convenient for packing either for the traveler or for shipping purposes, and it consists of certain novel features and details of construction as will be more fully described hereinafter and 20 finally pointed out in the claim.

I will now describe my invention, reference being had to the accompanying drawings, in which, Figure 1, is a side elevation showing the hanger assembled and ready for use. Figs. 2, 3, and 4, show the parts disconnected, and Fig. 5, is a detail view of the hook for holding the parts together when assembled as also means for supporting the hanger proper.

Similar letters of reference indicate corresponding parts in the several figures of the drawings.

A, represents the bottom or base section, B, and C, the side or supporting sections, 35 and D, the hook for holding the parts together as also means for supporting the hanger.

As will be seen from the drawings, the base section A, is provided with two notches 40 E, and E', in its lower edge, the purpose of which will be more fully described hereinafter, and the sides or supporting sections B, and C, are provided with elongated slots F, and F', at or near their lower ends,

and notches G, and G' at or near their upper ends.

In assembling my improved hanger, the base section A, is inserted through the slots F, and F', of the side or supporting sections B, and C; the upper ends of the side or supporting sections being drawn together at the top ends where the notches G, and G', interlock with each other. The hook D, is then slipped around and over the ends of these pieces which holds them rigidly together and also provides means for supporting the hanger proper.

As will be seen, my hanger will be cheap to manufacture, being simple in construction and easy to assemble. It is also very 60 convenient for shipping purposes as many hundreds of them can be packed within a very small space.

Having described my invention, what I claim and desire to secure by Letters Patent is:

A collapsible hanger, comprising a bottom or base section which is provided with two notches at or near its lower ends, two side or supporting sections provided with 70 elongated slots in one end thereof for receiving and holding the base section, notches formed in the upper ends of said side or supporting sections which adapts them to interlock with each other, together with a 75 hook which embraces the upper ends of said sections for holding them rigidly together and forming means for supporting the hanger proper, all substantially as shown and for the purposes described.

In testimony that I claim the foregoing as my own invention, I have hereunto set my hand in the presence of two witnesses.

LAYTON WATTON TOWNSEND.
